CLAIM

The ornamental design for the vent cover with frame, as shown and described.

DESCRIPTION

FIG. 1 is a perspective front to rear view of vent cover with a frame, showing my new design;

FIG. 2 is a front view thereof;

FIG. 3 is a rear view thereof;

FIG. 4 is a right side view with the left side view being a mirror image thereof;

FIG. 5 is a top view thereof; and,

FIG. 6 is a bottom view thereof.

The outer rectangle depicted in broken lines shown in FIG. 3 is intended to show boundary areas of the claimed design and form no part of the claimed design. Inner rectangular environmental elements depicted in broken lines shown in FIG. 3 form no part of the claimed design. The thick horizontal dashed lines of the drawing disclosure shown in FIGS. 1-3 illustrate portions of the article that form no part of the claimed design.
